Primary Examiner — George D. Kirschbaum*Assistant Examiner* — Joseph J Kukella(74) *Attorney, Agent, or Firm* — Oppenhuizen PLC; David L. Oppenhuizen(57) **CLAIM**

The ornamental design for a button cover, as shown and described.

DESCRIPTION

FIG. 1 is a perspective view of a button cover showing the new design;

FIG. 2 is a top view thereof;

FIG. 3 is a bottom view;

FIG. 4 is a front view; and,

FIG. 5 is a rear view.

In the drawings, the broken lines depict environmental subject matter only and form no part of the claimed design.
